CHANGE GIVING VENDING MACHINE AND
THE LIKE

Karl Hilding Lundqvist, Stockholm, Sweden, assignor to Kooperativa Förbundet Förening U. P. A., Stockholm, Sweden

Application November 7, 1939, Serial No. 303,212
In Sweden November 7, 1938

2 Claims. (Cl. 194—80)

Vending machines are known for receiving coins and delivering tickets, articles or the like and also coins corresponding to a balance, if any. A vending machine of this type for delivering tickets is shown and described in detail in the British Patent No. 440,763. In the known machines, the change delivering means cooperate with or are controlled by rotatable cam discs (delivery discs) secured to a common delivery shaft. The rotation of the delivery shaft is controlled by a summator, which is adapted to rotate through an angle proportional to the total value of the coins entered into the machine and which may preferably be constructed according to the principle disclosed in the U. S. Patent No. 2,173,264. Such machines, however, for reasons given in detail hereinafter, have, heretofore, been incapable of computing change amounts exceeding relatively small values. The object of the present invention is to produce a machine of this type which is adapted to give change up to relatively large amounts and which is simple in construction and operation.

The invention will be described more in detail hereinafter reference being had to the accompanying drawings. In the drawings, however, such devices and members have been omitted as are not necessary for understanding the invention or operate entirely independent of the delivery discs, which are the essential object of the present invention. Thus there have been omitted such devices as the ticket ejector means, means behind the coin slots for testing the genuineness of the coins, a suitable starting and drive device, means for releasing coins, the value or sum of which has not been sufficiently high, i. e. has been lower than the price for which the machine is adjusted. All such devices are entirely outside of the scope of the present invention and may be designed in any known manner.

On the accompanying drawings

Figure 1 is a plan view of a change giving vending machine, the members for entering the coins into and delivering the same from the machine being omitted from this figure for the sake of clarity.

Figure 2 is a section taken on the line II—II in Figure 1.

Figure 3 is a section taken on the line III—III in Figure 1.

Figures 4—8 show a series of delivery discs seen in the direction of the arrow in Fig. 1.

Figure 9 shows on a larger scale a section taken on the line IX—IX in Figure 1.

Figure 10 is a plan view of the parts shown in Figure 9.

Figure 11 shows on a larger scale a detail of the summator, the same being viewed along the section line XI—XI in Figure 12, which latter is a plan view of the said detail.

Figures 13 and 14 show on a larger scale the coupling between a toothed wheel of the driving mechanism of the machine and the summator in two elevations at right angles to one another.

Figure 15 shows a part of a coin delivery device in elevation.

Figure 16 shows, partly in section and partly in elevation a coin operated impulse mechanism.

Fig. 17 is a plan view of the same mechanism with the uppermost portion of Fig. 16 cut off and certain parts omitted.

Figure 18 shows means for ejecting change coins from the machine.

Figure 19 is a vertical section through a coupling device.

Figures 20—25 show another series of delivery discs also seen in the direction of the arrow in Fig. 1.

The summator illustrated on the drawings is constructed according to the principle disclosed in the U. S. Patent No. 2,173,264, the design of the members of the summator, however, and its mode of operation, in the present embodiment, differing somewhat from those of the patent. As shown, a number of sleeve shaped elements 1 are mounted on a shaft 4 rotatable in a frame 3. All the elements 1 are rotatable about shaft 4 with the exception of the last coupling element 1 on the right hand side of the machine which is fixed to the frame by means of a pin 2. Discs 104, having each a hub portion 21, are axially displaceably and rotatably carried on the shaft 4 alternately with the sleeve elements 1. Into suitable bores provided in the hub portion 21 of the first disc 104 on the left hand side of the machine, there project in axial direction pins 20, which are fixed in a hub portion 19 of a toothed disc 17. Similar pins 20 couple the first element 1 on the left hand side of the machine to the hub portion 21 of the next following disc 104 and so on. Each disc 104 corresponds to one coin denomination and carries on its periphery a single tooth or several uniformly spaced teeth. The number of teeth on each disc 104 is chosen in proportion to the corresponding coin denomination, the disc 104 corresponding to the highest denomination being provided with a single tooth. If the highest denomination is 200 and the lowest denomination is 5, the disc 104 corresponding to the lowest

denomination will thus have 40 teeth. The disc 104 corresponding to the value 10, said disc having consequently 20 teeth, is shown in Figures 11 and 12. The embodiment of the apparatus now described is adapted for Swedish currency. The mechanism is likewise adaptable for other monetary systems after slight alterations apparent to those skilled in the art.

Impulse members 6 actuatable by coins entered in the machine are capable of imparting a reciprocating motion to the discs 104, as will be described in more detail later on in connection with Figs. 16 and 17. By this reciprocation, the discs 104 are released for rotation and turned substantially in the manner disclosed in detail in the U. S. Patent No. 2,173,264. In the present case, however, the locking member for each disc 104 comprises two teeth 101, 102 which are axially and angularly offset with respect to one another and fixed to or formed from an arm 103 projecting radially from the adjacent sleeve member 1, see Figures 11 and 12. The spring force acting on the discs 104 is obtained by means of a helical spring 7 wound around a shaft 8, one end of said spring being at 105 fixed to said shaft 8 rotatably mounted in the frame 3 (see Fig. 1), the other end of the spring at 9 (Figure 2) being united with a toothed wheel 11 rotatable on the shaft 8. The spring tension is obtained by means of an arrangement described hereinafter more in detail.

The toothed wheel 11 meshes with a larger toothed wheel 13 on the shaft 12 (Figure 2), said wheel 13 in its turn meshing with a smaller toothed wheel 14 rotatable on the shaft 4. With the toothed wheel 14 is rigidly united a larger toothed wheel 15, in the present embodiment provided with two pins 16, said pins, lowest denomination in this case being five and the highest denomination two hundred, being adapted to be inserted into two of forty apertures 18 in the disc 17 (Figures 13, 14), which latter, together with its hub 19 is rotatably and axially displaceably mounted on the shaft 4. When the pins 16 project into the apertures 18 in the manner shown in Figures 1 and 14, the spring 7 through the medium of the toothed wheels 11, 13, 14 and 15 will strive to rotate the disc 17 in the direction indicated by an arrow in Fig. 2. However, the pins 20 couple the hub 19 of disc 17 and the sleeve members 1 (except the last one on the right-hand end of the machine) constantly to the hubs 21 of the next succeeding discs 104, respectively (counted from left to right in Fig. 1), and as long, as no coin is inserted, each sleeve element is locked to the preceding disc 104 by tooth 101 on arm 103 engaging a tooth of said preceding disc 104. Since the last member 1 at the right-hand end of the machine is held against rotation by means of the pin 2, the spring 7 is prevented from rotating the disc 17, as long as no coin is inserted into the machine. When, however, one or several coins are inserted into the machine, the impulse members 6, by axially reciprocating the corresponding discs 104, will free each reciprocated disc for a predetermined rotation. Upon movement in one axial direction, each disc 104, corresponding to an inserted coin, is released from the arresting tooth 101, whereby the released disc 104, all the members 1 and hubs 21 between said disc and the spring driven disc 17 and said disc 17 itself are permitted to rotate until the released tooth on the disc 104 strikes against the tooth 102 on arm 103. When the disc 104 then returns to its original axial posi-

tion, it is freed from tooth 102, and a further rotation of the reciprocated disc 104, intermediate members 1 and 21 and toothed disc 17 takes place, until the next tooth on the released disc 104 engages tooth 101. If the disc 104, corresponding to a coin value 200, which disc has only a single tooth, is actuated, the disc 17 will be permitted to carry out a full rotation; if the disc 104 corresponding to a coin value 5 and having 40 teeth is actuated, the disc 17 will rotate through an angle of 9°. If both said discs 104 are actuated simultaneously, the total rotation of wheel 17 will be 369°. Thus, the total angle of rotation of disc 17 and wheel 15 coupled thereto will always be proportional to the total value of the coins entered into the machine, as set forth in U. S. Patent No. 2,173,264. The disc 17 has on its periphery teeth with which a spring-actuated detent 70 cooperates.

The toothed wheel 15 meshes with a toothed wheel 23 secured to the rotatable main delivery shaft 22 of the machine, and the delivery discs 5, 10, 25, 50 on the said shaft controlling the delivery of certain coin denominations will, therefore, be turned by the spring 7 through an angle corresponding to the entered amount, when the pins 16 are inserted into the apertures 18 in the disc 17. In hitherto known machines all delivery discs have been rigidly secured to one common shaft adjustable in dependence upon the adjustment of the summator shaft. As long, as only small amounts are concerned this arrangement was sufficient. However, if the machine shall be used for entering amounts higher than 1 Swedish krona, for instance for prices up to 2 Swedish kronor, the summator shaft and the delivery shaft, respectively, must necessarily be capable of assuming forty various angle positions. Already this complicates the machine to a certain degree, but as soon as the limit of the capacity of the machine must be moved up to, for instance, 4 Swedish kronor, in which case the delivery shaft, the lowest unit being 5 Swedish öre, must be capable of assuming eighty various angle positions, the discs 5 will be of too great dimensions to make the machine practically usable, for the discs of the summator as well as of the delivery shaft must, of course, have a considerably greater diameter. With increasing diameter the momentum will also increase, and therefore abutments and the like must be made stronger. Moreover, the machine will also require greater motive power, but in spite thereof the machine will not be able to operate as quickly as a smaller machine with a delivery shaft adapted to assume a smaller number of angle positions.

The present invention, however, solves the problem in a very simple manner as regards construction. According to the invention it is thus possible to use a change giving vending machine, the summator shaft of which must not be able of assuming more than twenty positions at each revolution, although the same may be used for prices from 5 Swedish öre up to 18.95 Swedish kronor. In practical use, however, there will be no question of higher amounts than 4 to 5 Swedish kronor. According to the invention the discs 5, 10, 25 and 50 controlling the delivery of the lower coin denominations, as for instance the 5, 10, 25 and 50-öre pieces, are fast on the shaft 22. In an embodiment of the invention in which the highest coin denomination to be computed at a time is 1 Swedish krona, the shaft 22 is adjustable by the summator to twenty angle positions spaced 18° from one another. The discs

5, 10, 25 and 50 should, in this case, have the shape shown in Figures 4-7.

The corresponding disc 100, illustrated in Fig. 8, is secured to a separate rotatable auxiliary shaft 26, (see Fig. 1) which may be regarded as a continuation of the delivery shaft 22. The disc 100 is rigidly united with a toothed wheel 27, which meshes with a toothed wheel 29 mounted rotatably on one end of a shaft 28 being in turn rotatable in a frame portion. To the shaft 28 are secured, adjacent the toothed wheel 29, a toothed wheel 30, of the same shape and size as the toothed wheel 29, and, on the opposite end of the shaft 28, a toothed wheel 31 which is adapted to cooperate with a disc 33 having, in the embodiment of the invention illustrated in Figs. 4 to 8, a single tooth space 32, said disc 33 being fast on the shaft 22 (Figures 9, 10). A coupling wheel 36 carried by an arm 35 rockable about a shaft 34 is adapted to be brought into and out of driving mesh with the toothed wheels 29, 30. If the wheel 36 meshes with the toothed wheels 29-30, the disc 33, upon each full rotation of the shaft 22, will impart a turning movement to the wheel 31, said movement being transmitted via the wheels 30, 36 and 29 to the toothed wheel 27. The disc 100 will thus also assume an angle position corresponding to the entered amount.

In Figs. 4 to 8, the delivery discs 5, 10, 25, 50 and 100 are shown in their "no change" positions, which they assume if the sum of the inserted coins corresponds exactly to the price of the article sold by the machine. It will be understood, that the shaft 22, and, if the price of the article exceeds 1 krona, also the auxiliary shaft 26, must be adjusted to normal or rest positions in which the delivery discs are angularly displaced from their "no-change" positions in the direction opposite to that indicated by the arrows in Figs. 4 to 8 to an extent determined by the price of the article sold by the machine. This adjustment is effected as follows: While maintaining the driving connection between shafts 22 and 26, shafts 22 and 26 are put out of driving connection with the toothed wheel 15 and the segment gear 57, respectively. The shaft 22 is then turned in counterclockwise direction (as seen in Fig. 2) through an angle corresponding to the determined price of the article. Thus, if the determined selling price is 50 Swedish öre, the shaft 22 is turned, in the embodiment shown in Figs. 4 to 8, through an angle of 180°; if the price is 1 Swedish krona, the shaft 22 is turned through 360° and the auxiliary shaft 26 with the disc 100 is turned one step in counterclockwise direction (as seen in Fig. 2). After the adjustment of shafts 22 and 26, the shafts are again drivingly connected with the toothed wheel 15 and the gear 57, respectively, the cam 49, described in more detail later on, is reset on shaft 22 to the position shown in Fig. 2, and the machine is ready for operation.

If the selling price of the article is, for instance, 25 öre, the shaft 22 has been adjusted to a position in which the discs 5, 10, 25 and 50 are displaced 90° in counterclockwise direction (as seen in Fig. 2) from their "no-change" positions. Assuming, now, that coins to the value of 50 öre are inserted into the machine, the summator will release the delivery shaft 22 for a clockwise rotation through 180°, and this shaft with the discs 5, 10, 25 and 50 will thus be brought into a position in which 25 öre change are delivered, as will be described later on.

In a machine having a delivery shaft and cam

assembly, as illustrated in Figs. 4 to 10, the highest amount of change which can be delivered in a single operation is 2.95 kronor.

However, a machine, as shown in Figs. 1 and 2, provided with a delivery shaft and coin assembly, as illustrated in Figs. 20 to 25, is capable of delivering change up to 6.95 Swedish kronor in a single operation.

In this latter embodiment of the invention, the gear wheel 23 is geared to the toothed wheel 15 at the ratio 1 to 1, and the shaft 22 with the discs 5, 10, 25 and 50 is capable of assuming 40 angle positions spaced 9° from one another in accordance with the 40 angle positions of disc 104. The forty angle positions are indicated by dot-dash lines on the disc 5 in Fig. 20. All the delivery discs, 5, 10, 25, 50, 100 and 200, are shown in Figs. 20 to 25 in their "no-change" positions.

The auxiliary shaft 26 carries, fast thereon, in addition to the cam disc 100, the cam disc 200 controlling the two kronor coin change delivery device. The gear disc 33 is, in this case, provided with two diametrically opposed tooth spaces 32 (one of which is hidden in Fig. 2), so that the auxiliary shaft 26 will be turned one step, each time the shaft 22 has completed half a revolution.

The spring 7 is held permanently at a predetermined tension by means of the device described hereinafter.

On the shaft 8 is fixed a disc 38 having recesses 37. A toothed wheel 39 is disposed rotatably and axially displaceably on the shaft 8 adjacent the disc 38, said wheel 39 being provided with projections 40 corresponding to the recesses 37. In driving mesh with the toothed wheel 39 is a toothed wheel 106, which is driven by a motor not shown on the drawings. An adjustable helical spring 41 urges the wheel 39 against the disc 38 and strives to move the projections 40 to engage the recesses 37. The projections 40 will thus serve as driving members for the disc 38. After the projections 40 have rotated the disc 38 a certain number of revolutions and the spring 7 has received the desired tension, the spring 41 will allow the projections 40 owing to the resistance of the spring 7 to leave their engagement with the recesses 37. Immediately after the tension of the spring 7 has lowered, the spring having been allowed to rotate the toothed wheel 11, the spring 41 presses once more the projections 40 into engagement with the recesses 37. The tension of the spring 7 is thus held substantially constant.

The discs 5, 10, 25, 50, 100 and 200 are restored to their normal or rest positions at a predetermined stage of each operation of the machine by means of the following arrangement:

A shaft 42, which at a predetermined moment is rotated through 360° by means of a coupling 335 on the shaft 42, said coupling being described more in detail hereinafter, has secured thereto two cam discs 43 and 44. A follower 45, provided on a spring actuated arm 46 rockable about the shaft 4, is held pressed against the cam disc 43, and, upon rotation of the latter, the end 47 of the arm is displaced to a position in which it is disposed in the path of a projection 48 on the cam disc 49 secured to the shaft 22, away from its normal position, shown in full lines in Fig. 2, in which it permits said disc 49 to rotate in the direction indicated by an arrow in Figure 2. Against the cam face 107 of the cam disc 44 (Figure 3), there bears through spring action a pin 53 secured on an arm 52 rockable about a pivot 51. Upon the rotation of the cam disc 44,

the arm 52 will perform a rocking motion to and fro, and, by a fork member 55 united with the arm 52 and engaging a groove 54 in the hub portion 19 of the disc 17, the latter will be reciprocated on the shaft 4, and the apertures 18 of said disc will consequently engage and disengage the pins 16 on the toothed wheel 15.

Further cam discs 61 and 65 on shaft 42 actuate, during rotation of the latter shaft, Y-shaped arms 63 and 66, respectively, said arms being rockable about a shaft 62. The arm 63 is connected through a link 64 with the arm 35 carrying the coupling wheel 36, while arm 66 is connected with a link member 59. A gear segment 57 rockable about a shaft 56 and meshing with the toothed wheel 27 carries on a lever arm extending beyond its pivot axis a pin 60 guided in a longitudinal slot 58 of link 59. Elements 61, 65, 63, 66, 64, 59, 57 and 60 serve to restore the auxiliary delivery shaft 26 to its rest position, as will be described later on.

The mechanism for restoring the main delivery shaft and the auxiliary delivery shaft to their rest positions is claimed in my copending application Ser. No. 327,606.

The abovementioned coupling 335 for restricting the rotation of the shaft 42 to one revolution is substantially constructed as the corresponding coupling in the British Patent No. 440,763 and serves also here the same purpose, but owing to a slight alteration the coupling is described hereinafter with reference to Figures 1 and 19.

A coupling box 338 is fixed to the shaft 42. Into said box there extends a bushing or sleeve 336, having fixed thereto a toothed wheel 341, which is in driving mesh with the toothed wheel 39, and a cam member 342. An inwardly projecting tooth 345 on a ring 346 disposed radially displaceably in said box 338 for rotation therewith, is adapted to be engaged by the teeth 343 of said cam member when the ring 346 is shifted to its one radial end position, and to rotate box 338 and shaft 42 in the manner set forth in the British Patent No. 440,763. After a rotation of 360°, the projection 348 of the ring 346 through cooperation with the stationary pin 350 shifts the ring 346 back to its inoperative position, thus ensuring that only one full rotation of the shaft 42 is effected.

The coins are entered into the machine via coin chutes 108 (Figures 2, 16 and 17), the number of which in the present case corresponds to the number of discs 104 and the discs 5, 10, 25, 50, 100 and 200 respectively. The coins, in passing the coin chutes 108, cooperate with the corresponding impulse members 6, as will be described hereinafter in connection with Figs. 16 and 17. Each coin chute 108 is connected to a coin receptacle 109. Each coin ejection device comprises an ejecting member 111 adapted to be reciprocated by a gear segment 110 and an arm 113 adapted to be rocked upwards and downwards by a cam disc 112 on shaft 42, said disc being so shaped that the arm 113 retains the plunger 114 in the position shown in full lines in Figure 15 until the counting process has been finished and the delivery discs 5, 10, 25, 50, 100 and 200 of the machine have assumed their positions corresponding to the entered amount, said plunger 114 forming the bottom of the coin receptacle. The counting process having been finished and rotation of shaft 42 having been started, the arm 113 performs a rocking movement. The pin 115 on the underside of the plunger 114 is then allowed to move down and, according to the angle posi-

tion of the corresponding delivery disc, to bear against the periphery of the corresponding delivery disc or to enter some one of the recesses made in the disc as shown in dot-dashed lines in Figure 15. If the pin 115 bears against the periphery of the delivery disc, the ejecting member 111, being displaced and passing through apertures in the wall of the coin receptacle and through a groove 116 in the plunger 114, will not strike or take along any coin, but if the pin 115 enters one of the recesses in the corresponding delivery disc, the front end of the ejecting member strikes and pushes out one or more coins through the slot 117 in the receptacle, the depth of the recess entered by the pin 115 determining the number of coins ejected. The ejected coin falls through a coin chute 129 to the delivery opening of the machine.

How the segment gears 119 are rocked to and fro will be seen most clearly from Figure 18. This figure shows how the segments are fixed to a shaft 118 visible also in Figure 2. At one end of said shaft 118 there is fixed an arm 119 which by means of a link member 120 is united with a pin 122 eccentrically located on a disc 121. The rotation of the disc 121 fixed to the shaft 42 will thus rock the shaft 118 to and fro, and the segment gears through their cooperation with the teeth 123 of the members 111 will cause the latter to perform a rectilinear reciprocating motion in their guides 124 (Figure 2).

Above each coin receptacle 109 there is inserted in the coin chute 108 a plunger 126 having a central boring 125, Figures 16 and 17. One end of a hook-shaped member 127 fixed to the corresponding impulse member 6 bears against the plunger 126 and through the action of a draw spring 128 united with the member 6, which member is rockable about a pin 133, the member 127 strives to press the plunger into the position shown in full lines in Figures 16 and 17. At each coin chute 108 there is also a cross piece 131 interposed between two displaceable rods 130, said cross piece having fixed thereto a pin 132 of a smaller diameter than the boring 125 of the corresponding plunger 126. Furthermore, there is provided an angle lever 135 rockable around a pin 134, said lever being actuated by a spring 136 (Figure 16). One end of said lever is intended for cooperation with a notch 137 in the member 6 as will be described hereinafter more in detail.

When a coin 138 is inserted in a coin chute 108 the coin will remain in the position shown in Figure 16, the chute portion beneath the plunger 126 being laterally offset relative to the upper chute portion (see Fig. 16). If the rods 130, for instance by depression of an operating member accessible from the outside of the machine, are displaced in the direction indicated by an arrow in Figure 17, the inserted coin will prevent the pin 132 from entering the boring 125 in the plunger 126. The latter will instead be forced against the action of the spring 128 into the position indicated by dot-dashed lines in Figure 16. The member 6 is simultaneously caused to perform a rocking movement, one end of the arm 135 being thereby brought to engage the notch 137 and the corresponding disc 104 is axially displaced by the lower forked portion 139 of the member 6. The coin has simultaneously been brought into register with the offset downward continuation of the coin chute 108. If the rods 130 are now allowed to return to their initial position, the member 6 will for a short time be retained in its displaced position owing to the cooperation between

the arm 135 and the notch 137. Therefore, when the pressure of the pin 132 against the coin ceases and the coin is freed to fall down into the coin receptacle 109. Immediately before reaching its initial position the cross piece 131 brings the arm 135 out of engagement with the notch 137, the member 6 being thereby rocked back to its initial position by the spring 128. During the to and fro rocking motion performed by the member 6, the corresponding disc 104 is first released from tooth 101 and then from tooth 102 of the locking member 103 and is thus allowed to rotate under the driving force of spring 7 until it has reached an angle position in proportion to the entered coin denomination. The action of the spring 7 is transmitted to the discs 104 through the toothed wheels 11, 13, 14 and 15, the pins 16, the toothed wheel 17 and the coupling pins 20 between the hub portion 19 of the wheel 17 and between sleeve elements 1 and hubs 21 of discs 104. The discs 104 in the corresponding coin chutes 108 of which no coin has been entered have not been reciprocated, since the corresponding pins 132 have passed into the bores 125 of the plungers 126. Said plungers and the members 6 cooperating therewith have thus remained in their positions and the corresponding discs 104 have remained locked by the locking members 103 to the adjacent sleeve members 1.

A short summary of the entire counting process will be given hereinafter.

Coins amounting to a value equal to or more than the price of the article or the ticket are entered through the coin slots of the machine. By means of electrical contact devices in the coin chutes the electrical motor driving the toothed wheel 106 is put into function immediately after entering the first coin. During the entering of the coins the toothed wheel 38 and the disc 38 are thus rotated, i. e. the spring 7 is strengthened. When the required number of coins has been entered the rods 130 are displaced in the manner described above, and those discs 104, into the corresponding coin chutes of which coins have been entered, are displaced axially and turned to an angle position relative to the adjacent sleeve member 1 in proportion to the denomination of the entered coin. The toothed wheel 15, thus, rotates through a total angle proportional to the total value of all coins entered into the machine. Shaft 22 is rotated by gear 23 in mesh with toothed wheel 15, and this rotation of shaft 22 is transferred to the shaft 26 by means of the gearing 33, 31, 30, 36, 29 and 27 described before in detail. During said transfer the segment gear 51 rockable about a shaft 56 and meshing with the toothed wheel 27 is rocked in the direction indicated by an arrow in Figure 2, and the pin 60 guided in the slot 58 of link member 59 performs a movement corresponding to the movement of the segment gear 51.

After the counting process has been completed another operating member accessible from the outside is depressed, putting the coupling 335 into function via a pin 334. This may, of course, be effected in the manner set forth in the British Patent No. 440,763. This coupling having been put into function, the shaft 42 starts rotating and causes delivery of the article by any known means, as for instance those described in the British Patent 440,763. Simultaneously, arms 113 perform their downward rocking movements and immediately thereafter the ejecting members 11 are displaced towards the right (see Fig. 2). After the article and also the balance, if

any, have been delivered, the arms 113 and the members 111 return to their initial positions. The discs 5, 10, 25, 50, 100 and 200 are returned to their rest positions in the following manner. First, during the displacement of members 111 towards the right, the cam disc 43 rotating with the shaft 42 causes the end 47 of the arm 46 to assume the position in the path of projection 48 on cam disc 49 indicated by dot-dashed lines in Figure 2. Next, cam discs 61 on the shaft 42 operate the Y-shaped arm 63 and the link member 64 to rock the arm 35 in the direction indicated by the arrow in Fig. 2 thereby causing the coupling wheel 36 to leave its engagement with the toothed wheels 29, 30. Simultaneously, the arm 52, through the action of the cam face 107 of cam 44 on the pin 53, displaces the forked portion 55 and the disc 17 in such a way that the pins 16 of the wheel 15 cease to cooperate with the apertures 18 of the disc 17 which latter has been arrested by the summator in the angular position assumed at the end of the counting operation. As a result, the gears 11, 13, 14 and 15 are freed to transmit the turning force of the spring 7 once more to the toothed wheel 23 on the shaft 22. At this moment, the shaft 22 is still locked against rotation by the pins 115 being in engagement with the recesses of the corresponding delivery discs, but, when, upon continued rotation of shaft 42, the cam 112 rocks the arm 113 to lift the plungers 114 and pins 115, the shaft 22 is rotated in clockwise direction (as seen in Fig. 2) until the projection 48 of the disc 49 strikes against the end 47 of the arm 46, whereupon the shaft 22 stops with the discs 5, 10, 25 and 50 assuming their normal or rest positions. Immediately after the upward displacement of pins 115, the cam discs 65 displace, through the Y-shaped arm 63, the link member 59 in the direction indicated by the arrow in Fig. 2, and, when one end of the slot 58 strikes against the pin 60, the segment gear 57 is rocked in clockwise direction (as seen in Fig. 2). In this manner, the toothed wheel 27 and the shaft 26 with the discs 100, 200 are restored to their rest positions in a counterclockwise movement.

Towards the end of the rotation of shaft 42 through 360°, the cam 44 permits the fork 55 to return the disc 17 into engagement with the toothed wheel 15, whereupon the arm 46 is forced by the cam disc 43 to reassume its inactive lower position so that the shaft 22 is then retained in its angle position by the engagement between toothed wheel 15 and disc 17 and no longer by the end 47 of arm 46. Approximately simultaneously with the downward movement of the arm 46, the cam 65 returns the striker member 59 to its right-hand position without causing any movement of segment gear 57. Finally, the coupling wheel 36, having been retained in its angle position by a spring actuated locking roller 67, is returned into engagement with the wheels 29, 30 by the link 64, arm 63 and cam disc 61.

When the shaft 42 has completed a full rotation, the oblique surface of the projection 348 cooperates with the stationary pin 350 and returns the ring 346 to its initial position, whereupon the shaft 42 stops turning. Simultaneously, the current to the electrical motor is automatically broken. The machine is thus ready for a new operation.

As will be clear from the foregoing description, the discs 5, 10, 25 and 50 are rotated in the same (clockwise) direction during the restoring operation and during the counting operation, while the

discs 100, 200, during the restoring operation, are rotated in a (counterclockwise) direction opposite to their direction of rotation during the counting operation.

Having now described my invention, what I claim as new and desire to secure by Letters Patent is:

1. In a change giving vending machine having a rotary member, a coin controlled mechanism to rotate said member through an angle proportional to the total value of the inserted coins, a series of change delivery devices adapted to effect the delivery of coins of different denominations, respectively, and a series of change delivery discs controlling the different change delivery devices, 10 respectively, the combination of a main delivery shaft, having secured thereto some of said change delivery discs respectively controlling change delivery devices for coins of lower denominations, an auxiliary delivery shaft, having fixed thereto 15

at least one of said change delivery discs controlling a change delivery device for coins of one higher denomination, means drivingly connecting said rotary member with said main delivery shaft, and gearing between said main and auxiliary delivery shafts, said gearing being adapted upon rotation of said main delivery shaft through a predetermined angle to rotate said auxiliary delivery shaft through a predetermined smaller angle.

2. A machine, as claimed in claim 1, in which said gearing between said main and auxiliary delivery shafts includes an intermittent gear, adapted, whenever said main delivery shaft has rotated through an angle proportional to the value of the coins the delivery of which is controlled by said delivery disc on said auxiliary delivery shaft, to advance said auxiliary delivery shaft one step.

KARL HILDING LUNDQVIST.
